UNITED STATES PATENT OFFICE

169,991

HAT AND COAT HANGER

Solomon M. Sager, Fort Wayne, Ind.

Application March 4, 1952, Serial No. 18,766

Term of patent 3½ years

(Cl. D33—8)

To all whom it may concern:

Be it known that I, Solomon M. Sager, a citizen of the United States and a resident of Fort Wayne, State of Indiana, have invented a new, original, and ornamental Design for a Hat and Coat Hanger, of which the following is a specification, reference being had to the accompanying drawing, forming a part hereof.

Figure 1 is a perspective view of a hat and coat hanger, showing my new design;

Figure 2 is a top plan view of the hanger;

Figure 3 is a rear elevational view of the hanger;

Figure 4 is a side elevational view of the hanger; and

Figure 5 is a front elevational view of the hanger.

I claim:

The ornamental design for a hat and coat hanger, as shown.

SOLOMON M. SAGER.
